Specification of Letters Patent.

Patented Apr. 6, 1920.

Application filed May 18, 1919. Serial No. 298,147.

To all whom it may concern:

Be it known that we, CHARLES W. CASS and WILLIAM L. BAXTER, citizens of the United States of America, and residents of Salem and Beverly, respectively, in the county of Essex and State of Massachusetts, have invented new and useful Improvements in Clips, of which the following is a specification.

10 This invention relates particularly to clips for attaching skins, hides, pelts, and the like to a supporting frame such as disclosed in our former copending application Sr. No. 288,638, filed April 8, 1919, this application being in part a continuation of the former application.

The drying apparatus for this purpose heretofore provided and in common use is of two distinct types; the first is a board 20 upon which the damp skin is stretched and secured by tacks driven through the edge portion of the skin into the board. This apparatus is objectionable for many reasons. The skin or other stock is necessarily 25 damaged by the tacks, and as one side of the skin lies against the board the drying process is seriously retarded. The boards soon become very dry and highly inflammable under the heat of the drying room, 30 thus increasing the fire risk; and they wear out rapidly in service because the tacks have to be driven into substantially the same part of the board, with the result that that particular surface soon becomes disintegrated 35 and the tacks will not hold under the strains exerted by the drying skin.

In the attempt to eliminate the defects of "tacking", so-called, drying apparatus has been provided comprising essentially an 40 open frame in which the skin is stretched for drying by strings having at one end a metal clip or "toggle" which grips the skin, the other end of the string being secured to the frame. While these frames do away 45 with the damage to the skin caused by the tacks of the older device, and both sides of the skin are exposed during the drying process, they are very unsatisfactory in service. A relatively large number of 50 strings are required which, notwithstanding the exercise of due care, become tangled when a skin is placed upon the frame or removed therefrom. It takes a relatively long time to string and stretch the skin upon 55 the frame and to remove it; the length of the strings has to be changed for each

skin placed upon the frame, and the strings stretch individually under the strain of the drying skin so that a uniform strain is not maintained upon the skin during the drying 60 process.

In our said former application we disclosed an improved support for drying hides and the like comprising a frame and one or more sheets of wire mesh or other foraminated or reticular material yieldingly stretched in the frame, together with improved clips for attaching a hide to the foraminated sheet around the edges of the hide, the clips having movable jaws adapted 70 to grip the hide therebetween and having spurs adapted to hook into the openings of the foraminated support. The invention herein claimed comprises said clips together with modifications thereof. 75

The object of this invention is to provide clips which will securely grip damp and slippery hides and the like, which may be readily attached or detached to or from the stock, preferably with one hand, which 80 may be readily hooked to or unhooked from a suitable support, preferably by one hand while the hide is being stretched, and generally to simplify and facilitate both the construction and operation of the clips. 85

In the accompanying drawings,—

Figure 1 is a side view of one embodiment of the invention, showing the clip in closed position;

Fig. 2 is a similar view showing the clip in open position;

Fig. 3 is a central longitudinal section of the clip;

Fig. 4 is a side elevation of another embodiment of the invention, showing the clip in open position;

Fig. 5 is a central longitudinal section of the clip shown in Fig. 4 with the finger ring omitted, showing the clip in closed position;

Fig. 6 is a side view of the clip shown in Figs. 4 to 5, viewed from the right-hand side of Fig. 4;

Fig. 7 is a side view of still another form of clip;

Fig. 8 is a side elevation of the same 105 clip viewed from the left of Fig. 7; and

Fig. 9 is a central longitudinal section, on an enlarged scale, of the stock-engaging lip of the clip shown in Figs. 7 and 8.

The clip shown in Figs. 1, 2 and 3 comprises a band 1 of flexible steel or other suitable material bent until the ends are

disposed in juxtaposition. The juxtaposed ends of the clip are bent to form interfitting lips 2 and 3 adapted securely to grip a hide or the like when forced together. On the 5 left-hand side of the clip near the upper end thereof, a spur 4 is struck-up for the purpose of hooking the clip into a sheet of wire mesh or other foraminated support such as disclosed in our prior application, 10 this spur facing toward the stock-engaging end of the clip. On the same side of the clip near the stock-engaging end two ears 5 and 6 are struck-up from the opposite sides of the band 1, these ears extending substantially perpendicularly from the left-hand side of the clip to opposite sides of the right-hand side of the clip. Pivotally mounted in the ends of the ears 5 and 6 is 15 an arm 7 which has an inner end 8 projecting at approximately right-angles from the outer end thereof. The arm 7 is preferably pivoted to the ears 5 and 6 by means of pivot lugs extending outwardly from the arm in the region of the 90° bend into openings 20 in the ears 5 and 6, the ends of the pivot lugs being riveted over if desired to prevent the lugs from pulling out of the openings. These parts are so arranged that the projecting end 8 engages the right-hand side of 25 the clip near the stock-engaging end and forces it inwardly into stock-engaging position when the arm 7 is swung upwardly into the position shown in Fig. 1. In order to prevent the clip from flexing in the region engaged by the end 8 of the arm 7 the central portion of this part of the clip is pressed inwardly to form lateral flanges 9 and 10. In bending the band 1 the upper end is 30 somewhat enlarged so as to make the opening 11 sufficiently large to form a finger opening by which the clip may be grasped.

The clip illustrated in Figs. 4, 5 and 6 comprises an inner band 12 of flexible steel or other suitable material which is shaped similarly to the band 1 in Figs. 1 to 3. Extending along the outside of the band 12 is an outer band 13 which is provided with a spur 14 similar to the spur 4 in Figs. 1 to 3. The bands 12 and 13 are anchored together by means of a struck-up tongue 15 on the inner band extending into an opening 16 in the outer band. An opening 17 is provided in the right-hand side of the outer band 13 and on opposite sides of this opening pivot ears 18 and 19 are struck-up. An arm 20 is pivotally mounted in the ears 18 and 19, this arm having a projection 21 adapted to engage the right-hand side of the 40 inner band 12. The projection 21 is provided with a central lug 22 adapted to extend into a narrow slot 23 in the band 12 to prevent lateral movement of the right-hand side of the band. A finger-ring 22^a 45 may be secured to the upper end of the clip

as shown in Fig. 4, or the opening 23 may be employed as the finger-opening as illustrated in Fig. 5.

The clip shown in Figs. 7 to 9 is similar to that shown in Figs. 4 to 6 in that it 50 comprises an outer band 24, an inner band 25, a spur 26 on the left-hand side of the outer band and a handle 27 pivotally mounted in ears struck-up from opposite sides of an opening in the right-hand side of the 55 outer band. Instead of attaching a separate finger-ring, as shown in Fig. 4, a loop 34 is struck-up from the outer band 24, as shown in Figs. 7 and 8. Figs. 7 and 9 also illustrate the fact that the stock-engag- 60 ing lips of the clip need not be formed as shown in Figs. 1 to 5, but may be formed by striking-up pointed spurs 35, these spurs pointing upwardly and inwardly so as securely to engage the stock and prevent it 65 from pulling out of the clip. When providing spurs 35 the ends of the clip band are preferably made substantially parallel throughout the region of the spurs.

To attach our improved clip to a hide or 70 the like, the forefinger is inserted through the finger-opening to grasp the clip, and the jaws are closed over the stock by throwing the actuating arm into closed position. Owing to the relative positions of the finger 75 opening and the actuating arm, the arm may be actuated by the thumb of the hand supporting the clip, the relationship of the parts being particularly convenient in the 80 embodiments shown in Figs. 1 to 3 where 100 the finger opening extends transversely of the path of the actuating arm. After the clip has been clamped to the stock, the stock may be stretched by pulling the clip and when the stock is sufficiently stretched, the 105 supporting spur is hooked into the wire mesh or other suitable support. Owing to the fact that the attaching spur faces toward the stock-engaging end of the clip, the clip may be quickly attached or 110 detached to or from the support. To detach the clip from the stock the actuating arm 7 may be swung outwardly by the thumb of the hand supporting the clip inasmuch as the end of the arm projects outwardly in 115 a convenient position when the arm is closed.

What we claim is:

1. A clip comprising relatively movable jaws and a hooked spur adapted without 120 change of form to engage and be disengaged from an opening in a support therefor.
2. A clip comprising relatively movable jaws, a finger piece, and a hooked attaching spur disposed adjacent to said finger piece and adapted without change of form to engage and be disengaged from an opening in a support therefor. 125
3. A clip comprising relatively movable 130

jaws, and means engaging the outside of one of the jaws for forcing the jaws together, the clip having a finger opening arranged adjacent to said means so that said

5 means may be operated by one finger when the clip is supported by another finger of the same hand.

4. A clip comprising relatively movable jaws, and means for forcing the jaws together comprising a movable handle, the clip having a finger opening extending transversely of the path of said handle adjacent thereto so that the handle may be actuated by the thumb when the clip is 10 supported by a finger of the same hand.

5. A clip comprising relatively movable jaws, a hooked spur on one side adapted without change of form to engage and be disengaged from an opening in a support 15 therefor and means on the other side for closing said jaws.

6. A clip comprising relatively movable jaws, a spur on one side for attaching the clip to a support and means including a 20 movable handle on the other side for clos- 25

ing said jaws, the clip having a finger opening arranged to permit said handle to be operated by the thumb when the clip is supported by a finger of the same hand.

7. A clip comprising relatively movable jaws having stock-engaging lips, and means including a pivoted handle for forcing said lips together, the clip having a finger opening in the rear of said lips and said handle swinging toward said finger opening into 30 closed position. 35

8. A clip comprising relatively movable jaws having stock-engaging lips, and means including a pivoted handle for forcing said lips together, the clip having a finger opening in the rear of said lips and said handle swinging toward said finger opening into 40 closed position, said handle having a projecting end adapted to be engaged by the thumb to open said jaws when the clip is 45 held by a finger of the same hand.

Signed by us at Salem, Massachusetts, this thirteenth day of May, 1919.

CHARLES W. CASS.

WILLIAM L. BAXTER.
